UNITED STATES PATENT OFFICE

EDWARD C. EKSTROMER, OF REDWOOD CITY, CALIFORNIA, ASSIGNOR OF ONE-HALF TO JAMES F. GALLAGHER, OF BERKELEY, CALIFORNIA, AND ONE-HALF TO THE EDWARD C. EKSTROMER CORPORATION, A CORPORATION OF NEVADA

DRIVING MECHANISM FOR OIL-WELL PUMPS

Application filed March 12, 1930. Serial No. 435,141.

My present invention relates broadly to apparatus for converting rotary motion into reciprocating motion, and more particularly to an improved arrangement of apparatus of 5 the above character for driving reciprocating oil well pumps having a relatively long stroke.

The object of my invention is to provide an improved oil well pump driving mechanism 10 which can be lowered into an oil well as a unit upon the lower end of the oil discharge pipe.

Another object of my invention is to provide an electrically driven reciprocating 15 pump unit for deep well pumping that can be lowered into the well at the end of the oil discharge pipe and in which there is provided rotary electric motors and means for converting the rotary movement of said motor 20 into a reciprocating movement which can be imparted to the pump sucker rod.

A further object of my invention is to provide a new and improved apparatus for converting the rotary motion of an electric motor into a reciprocating motion, which when connected to a pump will operate the sucker 25 rod with a reciprocating movement.

Other objects and advantageous features 30 of my invention will be in part evident and in part set forth at length in the following description wherein I have outlined in full that form of apparatus which I have selected for illustration in the drawings accompanying and forming a part of this specification.

At the present time, oil well pumps of the 35 reciprocating type are operated by means of a motive power unit located on the surface at the top of the well. These units comprise a prime power, a walking beam which is oscillated by means of a pitman connected to the prime mover and a sucker rod which is attached to the walking beam and caused to move with a reciprocating movement as the walking beam is oscillated. The sucker rod 40 extends downwardly into the well where it connects to the moving parts of the pump. The use of such a sucker rod is attended with many undesirable features, some of which are: stretching, whipping, and its weight. 45 All of these undesirable features become more

exaggerated as the depth of the well increases and it is therefore desirable that some means be provided whereby these difficulties can be overcome.

In order to overcome these difficulties, I 55 propose to construct a prime mover element for operating a reciprocating oil well pump that can be lowered into the well and which will dispense with the use of the above referred to motive power units and its cooperating sucker rod. The greatest obstacle in providing such a unit is in providing a unit small enough to be inserted into the well casing, 60 which casing is of a relatively small diameter for such a purpose. This restriction in the size of such a unit, however, applies only to its horizontal or diametrical dimensions and since it can be made of almost any desired length, I propose to build an electro-mechanical power unit by employing a plurality of 65 smaller units, each of which is small enough to be inserted in the well.

For a better understanding of my invention, reference should be had to the accompanying drawings, in which I have shown by way of illustration and not of limitation apparatus which represents the best embodiment of my device now known to me. I desire to have it understood, however, that many changes and modifications can be made there-in without departing from the spirit of my invention.

In the drawings, wherein like numerals refer to like parts throughout the several views,

Fig. 1 is a vertical sectional view of the 75 lower portion of my improved pump and driving mechanism,

Fig. 2 is a vertical sectional view of the middle portion of my improved mechanism,

Fig. 3 is a vertical sectional view of the upper portion of my improved pump driving mechanism,

Fig. 4 is a vertical sectional view of a part of the mechanism taken on a plane at right angles to the plane of the sections shown in Fig. 3,

Figs. 5 and 6 are fragmentary vertical sectional views of the pump portion of my improved device,

Fig. 7 is a fragmentary vertical sectional 100

view of the reciprocating driving mechanism of my invention,

Fig. 8 is a fragmentary vertical sectional view showing stop devices which co-operate with the apparatus shown in Fig. 7,

Figs. 9, 10 and 11 are horizontal sectional views taken respectively along lines IX—IX, X—X and XI—XI of Figs. 7 and 8, and

Fig. 12 is a fragmentary detailed view in elevation showing the toggle mechanism.

In the drawings 10 designates an outer casing which is perforated throughout its length by the provision of suitable apertures 11 extending through the sides thereof. At the lower end of the outer casing 10 there is provided a suitable closure member 12 and attached to this closure member 12 and extending upwardly within the outer casing 10 there is a second or inner casing 13. The casing 13 is spaced from the outer casing 10 so as to provide an annular passageway 14 between the two casings through which the oil to be pumped may freely pass as will hereinafter be apparent.

Arranged within the inner casing 13 and at the lower end thereof as illustrated in Fig. 1, there is provided a plurality of induction motor units 15 which are connected together by suitable enclosed flange couplings 16.

Disposed above the motors 15 there is also provided an epicyclic reduction gear mechanism 17 which is adapted to transmit the high speed rotary movement of the motors to a shaft 18 at a lower speed. The shaft 18 is shown as connected to the epicyclic gear 17 through a coupling 16 similar to that disposed between the motor units 15, and surrounding the shaft 18 there is provided a suitable packing support 19 in which there is arranged packings 20 and 21 for the purpose of preventing a free flow of oil along the shafts at these points.

Formed integrally upon the shaft 18, or connected thereto by suitable couplings, there is provided a right and left hand spirally threaded section of shaft 22 which is adapted to be rotated continuously in one direction by the motors 15. The spirally threaded portion 22 of the shaft 18 is suitably supported upon roller bearings 23 and 24, as will hereinafter appear. Surrounding the spirally threaded shaft 22 I provide a suitable cylindrical casing 25 which is adapted to reciprocate axially within the inner casing 13 and along the spirally threaded portion 22 of the shaft 18. This casing 25 carries suitable nuts and other mechanism which are to be described in greater detail hereinafter. Projecting upwardly from the casing 25 I show a pair of connecting links 26 which are connected together at their upper ends by means of a portion 27 so as to form a yoke-like member. These links 26 are disposed so that they pass beyond the upper bearing support of the spirally threaded shaft 22 and

connect with a sucker rod 28 of a suitable pump 29.

All of the aforementioned parts of my improved device with the exception of the sucker rod 28 and pump 29 are disposed within the inner casing 13. At the upper end of the inner casing 13 where the sucker rod 28 emerges therefrom there is provided additional packings 29 and 30 which serve to prevent the admission of crude oil into the inner casing. The inner casing 13 as shown in Fig. 3 terminates at the packing 30, and from this point on the outer casing continues to a point where it is connected with a suitable ported fitting 31 which is adapted to establish a connecting passageway from the space between the casings 10 and 13 to the intake end of the pump 29.

In Fig. 4 the member 31 is shown as having two oppositely disposed ports 32 that merge into a single annular port 33 which communicates with the intake end of the pump 29.

As shown in Figs. 5 and 6 the pump is of the usual construction such as is provided in long stroke pumps of this character. In other words, it consists of a suitable piston 34 having packings 35 and a ball valve 36 at the lower end thereof. At the upper end of the pump there is also provided a suitable check valve 37. The pump 29 at its upper end is attached to an oil discharge pipe 38 which in addition to affording an outlet passage for the oil from the well also supports the pump 29 and the aforementioned pump driving apparatus in the well.

Before proceeding with a description of the apparatus as illustrated in Sheet 2 of the drawings, mention should be made of the manner of supplying the motors 15 with electric power. This is done by means of a three phase concentrically formed cable which extends downwardly into the oil well alongside the discharge pipe 38. The lower end of this cable extends into a terminal box 39 formed upon the fitting 31, as shown in Fig. 3. From the terminal box 39 three individual conductors extend downward in a suitably formed passageway and between the casings 10 and 13 to the several motor units 15.

In order to hold the casing 25 against rotation as the shaft 22 rotates, there is provided oppositely disposed keys 41 which project inwardly from the inner wall of the inner casing 13. These keys 41 extend along the walls of the inner casing 13 throughout the length of travel of the casing 25 and engage keyways 42 formed along opposite sides of the casing 25.

By referring to Fig. 7 of the drawings, it will be seen that the oppositely disposed right and left hand threaded nuts previously referred to and here designated by the numerals 43 and 44, are held in the casing 25 on opposite sides of a central partition 45, which is

secured substantially midway between the ends of the casing 25 by means of screws 46. At the outer ends of each of the nuts 43 and 44 the casing 25 is provided with end members 47 and 48 which are also secured to the casing by means of screws. Suitable ball bearings 49 and 50 are provided at the top and bottom of the nut 43, as are also similar bearings 51 and 52 at the top and bottom of the nut 44. The provisions of these bearings at the ends of the nuts 43 and 44 it will be understood, is to permit their free rotation when the shaft 22 rotates, so that when one nut is released it will ride freely up or down the shaft as the casing is driven by the other nut.

In detail, the nuts 43 and 44 are in every respect similar except that they are disposed in reversed positions upon the shaft 22. Because of this similarity, and in order to simplify my description, I shall only describe here the nut 43 and its co-operating parts. It will be understood that the description of nut 43 and its co-operating parts will also apply to the nut 44 and its co-operating parts.

On the upper end of the nut 43 there is formed a conical head 53 and firmly fixed to the nut along a portion of its length there is provided a number of conical members 54 which form a series of cone surfaces on the nut. Surrounding these cone surfaces there is also provided a corresponding number of conical ring-shaped members 55 which are adapted to frictionally engage the aforementioned conical surfaces upon the nut. The conical ring members 55 are keyed against rotation in the casing 22 but are free to move axially thereof so that when they move up or down, as will hereinafter appear, they will engage and disengage the cone surfaces on the nut 43. In the drawings the cone-shaped rings 55 are shown as carried by spacing rings 56. These rings 56, while they perform no novel function are necessary in order to facilitate an assembly of the apparatus.

The lowermost conical ring 55 is provided with a specially formed spacing ring 57. This ring 57 engages the top of a double acting toggle mechanism which comprises two vertically disposed toggles 58 and a horizontally disposed circular toggle 59. The bottom of this toggle mechanism rests upon a supporting seat or abutment 60 so that when the toggles 58 are extended, the cone clutches formed by the cone members 54 and conical rings 55 will be engaged and thus grip the nut 43 and hold it against rotation within the casing 25. The supporting seat or abutment 60 is carried upon a plurality of relatively stiff compression springs 61, which may be adjusted to provide the right amount of pressure when the clutches are engaged. At the upper end of the nut 43 there is also provided an additional set of relatively

weaker springs 62 which tend to disengage the clutch members when the toggles 58 are collapsed.

Connected to the horizontally disposed toggle 59 of the nut 43 and to a similar toggle 59' of the nut 44 there is shown a pair of axially extending and oppositely disposed rods 63. These rods extend in both directions from the toggles and project beyond the ends of the casing 25, where they are provided with flat annular plates 64 which surround the screw 22. These rods 63 are adapted to freely slide through the casing 25 and are attached to the toggles 59 and 59' so that when one is extended the other will be collapsed. With this arrangement of the rods 63 it will be seen that as they are moved up and down the casing 25 the toggles will be alternately extended and collapsed.

In order to control the actuation of the toggle mechanism, I provide suitable latching means at each end of the casing in the form of oppositely disposed latches 65 which engage the plate 64 as is clearly illustrated in Fig. 8 of the drawings.

Upon referring to this latter figure of the drawings it will be seen that the latches 65 at the top of the casing 25 have engaged the adjacent annular plate 64 and are holding the rods 63 in their uppermost position. It will also be seen that the latches 65 at the bottom of the casing 25 have released the adjacent plate 64 at this point.

When the parts are in the position here shown, the nut 43 will be held in clamped engagement with the casing 25 and as a result the whole assembly will be traveling upwardly along the shaft 22. As the casing 25 approaches the upper end of its travel the latches 65 will be engaged by an annular collar 66 which will, as the casing continues to move upwardly, move the latches 65 outwardly and cause them to release the plate 64 and the rods 63. Prior to the engagement of the latches 65 with the member 66, the plate 64 will, however, have engaged a yielding sleeve 67 which is yieldingly held by means of a spring 68 carried within a stationary housing 69 secured to the inner casing 13, as illustrated in Fig. 9. The yielding sleeve 67 is so proportioned that it will store up energy just prior to the release of the latches 65 and expend its energy to push the rods 63 downwardly and thus collapse the toggle 59 and extend the toggle 59'.

The travel of the sleeve 67 is designed to be sufficient to force the rods 63 downwardly far enough to permit the lower latches 65 engaging and holding the lower annular plate 64 in this second or lowermost position. Arranged adjacent to the lower end of the screw shaft 22 there is also provided a housing 70 that carries parts corresponding to those just described in connection with the housing 69, which parts function in a similar manner to

reverse the action of the toggle mechanism and thus cause the casing 25 to again travel upwardly after the lower latches 65 have released the lower plate 64.

5 In order to properly support the spirally threaded shaft 22 I provide a suitable suspension bearing 71 in the housing 69 so that when the mechanism is operating on the up-stroke of the pump, which is the power stroke, 10 the screw 22 will be placed under tension rather than compression and as a result a bowing of the shaft 22 will be prevented.

15 Figs. 10, 11 and 12 show various details of construction which is believed will be readily understood without a further description thereof.

The operation of my improved mechanism is as follows:

20 It will be assumed that the motors 15 have been energized and are rotating at the proper speed and that the epicyclic gear 17 is transmitting a suitable rotary movement to the shaft 18. This will cause the spirally threaded portion of shaft 22 to rotate and when the 25 parts contained in the casing 25 are in the position shown in Fig. 7, the casing 25 will be moving upwardly as a result of the nut 43 being engaged by the clutch members previously described. As the casing 25 moves up- 30 wardly it will transmit through the oppositely disposed rods 26 an upward movement of the sucker rod 28 which will impart a similar movement to the piston 34 of the pump 29, as will be readily understood.

35 When the parts reach the position illustrated in Fig. 8 the latches 65 will engage the annular member 66 and be forced outwardly to a position where they will release the upper plate 64 carried by the rod 63, 40 and the previously stored energy of the spring 68 will act through sliding sleeve 67 to force the rods 63, which are attached to the toggles 59 and 59', and thus collapse the toggle 59 and extend the toggle 59'. When 45 the toggle 59 is collapsed the nut 43 will be released and may then freely turn as it slides down the shaft 22. At the same time the nut 44 will be firmly gripped against rotation within the casing 25 and will travel 50 down the shaft 22 by reason of its spiral engagement therewith and thus carry the casing 25 and its attached mechanism downwardly until the lowermost toggles 65, which will now be in their latching position, are released 55 and the above operation again repeated.

While I have, for the sake of clearness and in order to disclose my invention so that the same can be readily understood, described and illustrated specific devices and arrangements, I desire to have it understood that this 60 invention is not limited to the specific form disclosed but may be embodied in other ways that will suggest themselves, in view of this broad disclosure, to persons skilled in the art. 65 It is believed that this invention is broadly

new and it is desired to claim it as such so that all changes as come within the scope of the appended claims are to be considered as part of this invention.

Having thus described my invention, what I claim and desire to secure by Letters Patent is:

1. A driving mechanism for reciprocating pumps and the like comprising, a double acting screw adapted to be driven in one direction, a pair of nuts upon said screw adapted to be driven there along when held against rotation, one of said nuts having a right-hand thread and the other a left-hand thread, a casing surrounding said nuts having connection with a reciprocatable element, and means carried by said casing adapted to automatically grip said nuts alternately to thereby cause said casing and said reciprocatable element to move with a reciprocating movement as 85 said screw is rotated.

2. A driving mechanism for reciprocating pumps and the like comprising, a double acting screw adapted to be driven in one direction, a pair of nuts upon said screw adapted to be driven there along when held against rotation, one of said nuts having a right-hand thread and the other a left-hand thread, a casing surrounding said nuts having connection with a reciprocatable element, friction 95 clutches carried by said casing adapted to automatically grip said nuts alternately as they reach the end of their travel, and means for alternately actuating said clutches to thereby cause said casing and said reciprocatable element to move with a reciprocating movement as said screw is rotated continuously in one direction.

3. A driving mechanism for reciprocating pumps and the like comprising, a right and driven in one direction, traveling nuts upon left-hand threaded screw adapted to be said screw having threads cut in right and left-hand relation and adapted to be driven there along when held against rotation, a 110 casing surrounding said nuts having connection with a reciprocatable element, nut gripping means carried by said casing adapted to alternately grip said nuts to thereby cause first one nut and then the other to be driven along said screw, and means for limiting the travel of said casing adapted to actuate said gripping means, whereby said casing and said reciprocatable element will be automatically moved with a reciprocating movement as said screw is rotated.

4. A driving mechanism for converting rotary motion into a reciprocating motion comprising, a shaft having right and left-hand spiral threads formed thereupon, right and left-hand nuts in threaded engagement with said shaft adapted to be driven there along when held against rotation, a casing surrounding said nuts adapted to hold them 125

in spaced relation and freely rotatable, a yoke carried by said casing adapted to connect with a reciprocatable element, co-operating cone clutch members carried by said nuts and said casing, means co-operating with said cone clutch members adapted when actuated to cause them to alternately engage and disengage said nuts whereby said casing will be caused to reciprocate upon said shaft and drive said reciprocatable element.

5. A driving mechanism for converting rotary motion into a reciprocating motion comprising, a shaft having right and left-hand spiral threads formed thereupon, right and 15 left-hand nuts in threaded engagement with said shaft, an axially movable casing surrounding said shaft adapted to hold said nuts in spaced relation and freely rotatable, a yoke carried by said casing adapted to connect with a reciprocatable element, co-operating 20 clutch members carried by said nuts and said casing, toggle devices co-operating with said clutch members adapted when actuated to cause them to engage and disengage, a toggle operating means projecting beyond the 25 ends of said casing connected with said toggles, stops at the ends of said shaft adapted to engage said toggle operating means and actuate said toggles whereby said casing and 30 yoke will be caused to reciprocate upon said shaft as it is driven in one direction.

6. A driving mechanism for converting rotary motion into a reciprocating motion comprising, a shaft having right and left-hand 35 spiral threads formed thereupon, right and left-hand nuts in threaded engagement with said shaft, adapted to be driven there along when held against rotation, a casing surrounding said shaft adapted to hold said nuts in spaced relation and freely rotatable, a yoke 40 carried by said casing adapted to connect with a reciprocatable element, co-operating cone clutch members carried by said nuts and said casing, toggle devices co-operating with 45 said cone clutch members adapted when actuated to cause them to engage and disengage, to thereby grip and release said nuts and thus cause said casing to reciprocate upon said shaft, stops at the ends of said shaft 50 adapted to limit the movement of said casing, and means carried by said casing adapted to engage said stops and actuate said toggles, whereby said casing and yoke will be 55 caused to reciprocate as the shaft is driven in one direction.

7. In a toggle mechanism for actuating annular clutch members surrounding a rotating shaft the combination of, a rotatable 60 shaft, a stationary abutment surrounding said shaft, a plurality of axially movable clutch elements, a pair of toggles on opposite side of said shaft disposed between said abutment and said movable clutch elements 65 adapted to move said clutch elements into

an operative position when extended, and a third toggle having bifurcated arms which straddle said shaft adapted to extend said first toggles when it is extended.
